United States Patent Office

Des. 177,576
Patented May 1, 1956

177,576

ASH TRAY

Julio J. Marsella, North Providence, R. I.

Application December 13, 1954, Serial No. 33,518

Term of patent 3½ years

(Cl. D85—2)

Fig. 1

Fig. 2

Fig. 3

Fig. 4

Fig. 1 is a front perspective view of an ash tray, showing my new design;

Fig. 2 is a top plan view thereof;

Fig. 3 is a side elevational view thereof; and

Fig. 4 is a rear elevational view thereof.

I claim:

The ornamental design for an ash tray, as shown.
